PRINTING PRESS JOGGER

Filed Oct. 15, 1929

INVENTOR:

Julius Zebulon,
of John Elias Jones,
attorney.

UNITED STATES PATENT OFFICE

JULIUS ZEBELEAN, OF COVINGTON, KENTUCKY

PRINTING PRESS JOGGER

Application filed October 15, 1929. Serial No. 399,537.

This invention relates to jogger or evener devices used at the delivery end of printing-presses, notably of the cylinder type having a horizontal freshly-printed sheet carrier 5 and adapted to provide evenly piled, unsmeared finished sheets ready for packing in boxes or wrappers and subsequent use.

The prime object of the invention herein is to provide a peculiar form of what is commercially termed or catalogued as "pusher finger-blades" and in common shop parlance as "back-kickers", such peculiar form of each finger-blade being composed of a flat finger or blade that is flexibly mounted under retractile spring tension on a transverse rock-bar at the tail or delivery end of a cylinder press and adapted to lie flat or horizontally in the press until the sheet-carrier reaches a point in its onward or forward delivery-stroke where said rock-bar is timed to make a quarter-turn so as to bring the blade to an upright position immediately back of the rear edge of the freshly-printed sheet that is in motion toward its final deposit on the delivery-board, and thereby preventing the said rear edge of said freshly-printed sheet reacting backwardly when electrostatic or like undue conditions are present beneath the sheet and retard its full seating or deposit in evenly piled form and unsmeared condition on said delivery-board, and thus also preventing said sheet moving backwardly into the press for crumpling or crushing therein and otherwise choking it up for retarding the further proper advance of succeeding freshly-printed sheets, and said flexibly mounted blade being also adapted to be depressed on its hinge joint into horizontal or prostrate position so that the end cross-bar of the backwardly moving sheet carrier-frame, on its return stroke, will ride freely over the otherwise normally prostrate finger-blades and ready for the next forward or advance stroke of the freshly-printed sheet-delivery devices, and thereby performing the most essential feature of my invention herein of having the sheet-carrier retreat without any liability or danger of breaking any of the said upright finger-blades after setting-action on the sheet and that has been very materially wanting in

the use of the stiff and inflexible rubber or fiber blades heretofore in general, extensive use and quite frequently fractured and broken off when their mounting rock-bar chanced to fail to rock or was improperly timed in the adjustment of the machine by the press attendant, thereby causing considerable expense in such breakage and much loss of time in the use of the press, as well as delay in getting out orders.

The details of structure of my improved pusher finger-blade or jogger will be fully hereinafter described in connection with the accompanying sheet of drawings, in which—

Figure 1 is a plan view of the broken-off rear delivery-end of a cylinder printing-press, of the horizontal, face-up printed sheet delivery type and with a series of my improved safety, emergency pusher finger-blades mounted in active position within its frame; Fig. 2, a side elevation of Fig. 1, taken from the right-hand end thereof; Fig. 3, a full-size front elevation of my improved device mounted in place on a fragmentary portion of its transverse rock-bar; Fig. 4, a vertical section taken on the dotted line 4, 4, of Fig. 3; Fig. 5, a view similar to Fig. 3, but of the reverse side or back of the finger-blade; and Fig. 6, a plan view of the blade, but on a slightly larger scale than that of the three previous views, and omitting the rock-bar.

The ordinary delivery-end of a horizontal sheet-carrier type of cylinder printing-press shown in Figs. 1 and 2, has a transverse rock-bar or shaft 7 mounted in the side frame bars 8, 8, at its opposite ends and the pusher finger-blades 9 (taking each one as a unit) are mounted in a suitable spaced row thereon between the usual guard-arms 10 that extend forwardly from a rear cross-bar 11 and under which the freshly-printed sheets are carried and then deposited on the delivery-board 12, the latter part as best shown in Fig. 2. An upright guard or stop-plate 13 is provided at the extreme rear end of the said delivery-board to retard the further advance movement of the said freshly-printed sheets, which is the end of their usual journey in the press.

The usual clamping grips 14 (seen dotted

in Fig. 2) are provided at the rear end of the said sheet carrier-frame for gripping the respective sheets during their travel in the delivery part of the press and subject to release-action when the successive sheets have reached the end of their said journey in the press.

15 indicates a suitable base-block having a hole 16 for engagement with the said rock bar or shaft 7, a set-screw 17 being used to adjustably and detachably secure the lower plate 18 of the pusher finger-blade 19 thereon. The said plate 18 is set in non-shifting position in the shouldered portion 20 of the upright projection 21 of the said base-block 15 and removably secured by means of screws 22. An integral arm 23 extends at a right-angle from the rear face of said plate 18 and it has an eye at its outer end to which is hooked the outer end of a retractile spiral spring 24, the latter extending, at an upward slant, for hook-connection at its inner end with a rearwardly-extending eye 25 in the lower part of the blade 19. The blade 19 has hinge-connection 26 with the angular ears or lugs 27, 27, at the upper end of the plate 18, a pair of suitable upwardly-extending stops 28, 28, being provided on said latter-named plate 18 for preventing any backward swinging of the said blade 19 but not interfering with its forward swinging or hinging flexible action when necessary. The said arm 23 extends from said plate 18, at the base of the space or gap between the said upright stops 28, 28, as best seen in Figs. 4, 5 and 6, and the said spiral spring 24 retreats or drops down into the said space or gap when the blade 19 is swung or hinged from its upright extended position into its prostrate relief position for the rear or return movement of the sheet-carrier and thus escaping any undue chance of the said blade being broken off or damaged in such return movement.

45 The device is preferably made of metal throughout, but, if desired and believed beneficial or feasible, otherwise, for economy or convenience, the finger-blade may be made of rubber or fiber and suitably hinged to the base parts of the pusher-structure to obtain the advantages and emergency safety (against blade damage) features of the metal device shown and described herein.

55 In Figs. 1 and 2, it will be seen that the carrier-frame A has a pair of propelling pitmen B, B, and at its fore end a pair of roller-trundles D, D, that reciprocate on the pair of track-bars C, C, for the ordinary reciprocal movements of the said carrier-frame A so as to properly grip and carry or propel the successive freshly-printed sheets as they emerge from the printing mechanism of the press, face up, as in the common form of cylinder press, and then release said sheets into evenly piled form on the delivery board or 60 table, with the substantial, emergency aid of

my improved jogger or "back-kicker" (shop parlance) in attaining said evenly piled and accompanying unsmeared form or condition.

70 In said Fig. 2, I have shown the crank-arm lever device 7^a that is preferably used to rock the cross bar or shaft 7 on which a series of my pusher finger-blades are mounted and duly hinged under retractile spring tension.

I claim:

75 As an article of manufacture, a pusher finger-blade or paper-jogger for use in printing-presses and the like, the same comprising a main blade-member and a fastening plate-member, said blade-member being flexibly mounted on the upper edge of the said fastening plate-member and the latter, in turn, being adapted to be secured for jogger or evener use on a rock-shaft in the delivery-end of the press.

80 In testimony whereof I hereunto affix my signature.

JULIUS ZEBELEAN.
